DEVICE FOR CUTTING GLASS

Harold A. Perilstein, Cynwyd, and Harry Wandel, Cornwall Heights, Pa., assignors to Stott-Hecht Glass Works, Philadelphia, Pa., a corporation of Pennsylvania

Application April 20, 1953, Serial No. 349,854

5 Claims. (Cl. 33—42)

1

The present invention relates generally to the cutting of glass and more particularly to apparatus for producing an accurate score line on a sheet of flat glass or the like.

An object of the present invention is to provide a simple and inexpensive, yet accurate, device for scoring a sheet of glass or the like along a line parallel to, and spaced an adjustable distance inward from, one edge of the sheet, so as to enable the sheet to be thereafter broken along an accurately predetermined line.

Other objects and advantages of the present invention are apparent in the following detailed description, appended claims and accompanying drawings.

For the purpose of illustrating the invention, there is shown in the accompanying drawings one form thereof which is presently preferred and which has been found in practice to give satisfactory results; it being understood, however, that the invention is not limited to the precise arrangements and instrumentalities shown, and that the various parts and elements can be variously arranged and organized without departing from the spirit of the invention.

Referring to the accompanying drawings in which like reference characters indicate like parts throughout:

Figure 1 is a top plan view of a glass scoring device forming one embodiment of the present invention.

Figure 2 is a bottom plan view of the embodiment of Fig. 1.

Figure 3 is a side elevational view of the embodiment of Figs. 1 and 2, on a somewhat enlarged scale.

Figure 4 is a longitudinal cross-sectional view, taken generally along the line 4—4, on the same scale as Fig. 3.

Figure 5 is a cross-sectional view taken generally along the line 5—5 of Fig. 1.

Figure 6 is a transverse cross-sectional view, taken generally along the line 6—6 of Fig. 1.

The embodiment of Figs. 1—6 may include an elongated body 20 of inverted U-shaped cross-sectional configuration, having a slot 22 extending longitudinally along the major portion of its top wall 24 but terminating somewhat short of the ends of said wall.

The wall 24 is also provided with a transverse slot 26 disposed somewhat outward of one end of the slot 22. A block 28 is secured within the channel of the body 20 outward of the slot 26, while a second block 30 is similarly secured within the channel just inward of the slot 26. The

2

opposed faces of the blocks 28 and 30 are generally coplanar with the sides of the slot 26 so as to form a generally rectangular opening 32 extending downward through the body 20, as best indicated in Figs. 1 and 4.

The outer block 28 is provided with a longitudinally-extending screw-threaded opening, through which extends the screw-threaded stem 34 of a clamping member 36 having an enlarged head 38 at its inner end (i. e., within the opening 32) and a winged operating handle 40 at its outer end. It can be seen that manipulation of the handle 40 causes longitudinal movement of the member 36 so as to bring the head toward or away from the inner block 30. A conventional glass cutter 42, having a hard steel cutting or scoring wheel 44 journaled in a bifurcated end 46 thereof in the usual manner, is constructed and arranged to be inserted within the opening 32 so that the wheel 44 protrudes downward somewhat beyond the body 20, as shown in Fig. 3, whereupon the handle 40 is manipulated to move the member 36 inwardly so as to clamp the cutter securely in place between the head 38 and the inner or seating block 30.

A guide-member, indicated generally by the reference character 48, is movably mounted upon the body 20 in a manner to be hereinafter described.

The guide-member 48 includes an elongated U-shaped channel portion 50 disposed within, and slidable relative to, the inverted longitudinal channel of the body 20, as best shown in Figs. 2, 4 and 6. The bottom wall 52 of the channel portion 50 is apertured adjacent its forward end (i. e., the end nearer the glass cutter 42) so as to receive the stem 54 of an upwardly directed bolt 56 having a head 58. The major portion of the stem is screw-threaded. However, the lowermost portion (i. e., the portion nearest the head 58) is preferably left unthreaded, as at 54-a, and is adapted to receive an apertured roller 60 (of brass or other similar material) which is rotatably held intermediate the head 58 and the wall 52.

A threaded spacing nut 62 having a hexagonal head 64 and an upwardly-directed reduced-diameter shank 66 is mounted upon the threaded portion of the stem 54; the nut 62 being disposed, in most part, within the channel portion 50, but having its shank 66 extending within the slot 22, as best shown in Fig. 4.

A cross-piece 68 of inverted U-shaped cross-sectional configuration, having a top wall 70 and side walls 72, also forms part of the guide-member 48. The central portions of the side walls 72

are cut out so as to permit the cross-piece 68 to fit over and straddle the body 20 in right-angular longitudinally-slidable relation thereto. The top wall 70 is centrally apertured to permit the upper end of the bolt stem 54 to protrude therethrough. A second threaded spacing nut 74 is mounted upon the upper end of the stem 54, with its hexagonal head 76 disposed above the wall 70 and its downwardly-directed reduced-diameter shank 78 extending downward through the aperture in the wall 70 and into abutment with the upper end of the shank 66, as shown in Fig. 4. A washer 80 may be fitted about the shank 78 intermediate the head 76 and the wall 70.

As is apparent from Fig. 4, the two spacing nuts 62 and 74 and the bolt 56 interconnect the channel portion 50 and the cross-piece 68 rigidly, and yet so as to permit longitudinal sliding movement of the guide-member 48 along the body 20, as well as free rotation of the roller 60 upon the lowermost unthreaded portion 54-a of the stem 54.

Disposed within the inverted channel of the cross-piece 68 are left and right insert-pieces 82 of U-shaped cross-sectional configuration, which extend from the central cut-out portions of the walls 72 to the opposite outer ends thereof. The wall 70 is provided with openings spaced somewhat inward from the outer ends thereof, while corresponding aligned openings are provided in the bottom walls 84 of the insert-pieces 82; each pair of aligned openings being adapted to receive the stem 86 of an upwardly-directed bolt 88 having a head 90. A roller 92 is rotatably mounted upon the lowermost unthreaded end 86-a of the stem, intermediate the head 90 and the wall 84. A spacing nut 94 is screw-threadedly mounted upon the stem 86 above the unthreaded end thereof; the hexagonal head 96 of the nut 94 being preferably seated against the upper face of the wall 84, while the upwardly-directed shank 98 is adapted to bear against the lower face of the wall 70. A washer 100 and nut 102 are positioned upon the uppermost protruding end of the stem 86 and, when tightened, serve to secure the bolt 88 firmly to the wall 70 while permitting free rotation of the roller 92.

The insert-pieces 82 may be press-fitted into the channel of the cross-piece 68 so as to require no additional connection or support. However, if desired, the threaded portion of each stem 86 may be lengthened to extend slightly below the wall 84 and a separate lock nut (not shown) may be placed thereon (intermediate the wall 84 and the roller 92) so as to provide additional support for the insert-piece.

As indicated in Fig. 5, the cross-piece 68 and each insert-piece 82 forms an enclosed right-angular boxlike structure on either side of the body 20 and serves to maintain the cross-piece 68 in accurate right-angular relationship to the body 20.

The two rollers 92 and the roller 60 are of the same size and are in alignment, transversely relative to the body 20, so that, if the rollers are positioned against the straight edge of a sheet or pane of glass G as shown in Figs. 1 and 3, the body 20 will extend at right angles to said straight edge.

The bottom wall 52 of the channel portion 50 is provided with a second aperture, spaced somewhat inward of its aforementioned forward end; the aperture being adapted to receive the threaded stem 104 of an upwardly-directed bolt 106 having a head 108 disposed on the underside of the

wall 52. The stem 104 protrudes upward through the slot 22 and through an aperture in a triangular backing plate 110 resting upon the top wall 24 of the body 20; a washer 112 and wing-nut 114 being provided upon the uppermost portion of the stem 104. The backing plate 110 is provided with a forward edge 116 disposed at right angles to the axis of the body 20 and constructed and arranged to bear against the rear edge of the cross-piece 68, as shown in Figs. 1-4. This provides additional support for the cross-piece 68 and guards the cross-piece against accidental displacement from its necessary right-angular relationship with respect to the body 20.

When the wing-nut 114 is loosened, the guide-member 48 is free to move longitudinally along the body and can be manually adjusted to position the cutter any desired distance inward of the free edge of the sheet of glass G, after which the wing-nut is tightened to lock the guide-member securely to the body.

The device is then positioned against the sheet of glass to be cut, so that the rollers 60, 92, 92, bear firmly against the edge of the glass, while the wheel 44 of the cutter 42 rests upon the top surface of the glass, with the axis of the wheel parallel to the axis of the body 20, as indicated in Figs. 1-3.

It is apparent that, if the guide-member 48 is then moved manually along the straight edge of the sheet of glass G (i. e., vertically in Fig. 1), the cutting wheel 44 will roll along the top surface of the glass as the rollers 60, 92, 92, roll along the side edge, thereby producing a score line extending parallel to, and spaced a predetermined distance inward from, the free edge. The sheet of glass can be broken cleanly along the score line thus produced, in a manner well known in the art.

It can be seen that, by simply loosening and retightening the wing-nut 114, the glass worker or glazier can adjust the device to cut sheets of glass into different-size smaller sheets or panes having absolutely parallel sides (within the tolerances normally required), so long as he has an original straight edge to work from.

When the cutting wheel becomes worn or dull, the cutter can be quickly and easily replaced by simply loosening the clamping member 36 in the manner described above.

The body 20, the channel portion 50, the cross-piece 68, and the insert pieces 82 can all be formed easily and inexpensively from commercially available U-shaped metal channel; preferably of aluminum or other light-weight metal or alloy so as to minimize the total weight of the device and to make it convenient for a worker to use and carry about. The rollers, bolts, spacer nuts, etc. are all commercially available items, while the triangular plate 110 can be easily cut or stamped from sheet aluminum or other suitable material. The device can be assembled from its component parts in a matter of a few minutes.

The present invention can be embodied in other forms and, therefore, the above-described embodiment is to be considered, in all respects, merely as illustrative, and not restrictive; reference being made to the appended claims, rather than to the foregoing specification, as indicating the scope of the invention.

Having thus described our invention, we claim as new and desire to protect by Letters Patent the following:

1. A portable glass cutting device comprising

an elongated body of inverted U-shaped cross-sectional configuration having a slot running longitudinally along its top wall, means for mounting a glass cutting tool at one end of said body, a guide-member mounted upon said body and movable longitudinally therealong, said guide-member including a portion disposed within the channel of the body and a cross-piece slidably straddling the body in right-angular relationship thereto and connected to the channel-disposed portion by a bolt passing through said slot, clamping means for releasably locking said guide-member to said body, a roller mounted upon said connecting bolt and a plurality of aligned rollers mounted upon said cross-piece on either side of the body, the rollers being disposed on the underside of the cutting device at right angles to the axis of the body and being positionable against an edge of a sheet of glass or the like whereby the cutting tool will extend downward and into contact with the upper face of the sheet; the cutting tool producing a score line parallel to, and spaced a predetermined distance inward from, said edge when the device is manually moved so that the rollers ride along the edge.

2. A construction according to claim 1 wherein the cross-piece is also of inverted U-shaped cross-sectional configuration, with the sides cut out at the center to fit over the body.

3. A construction according to claim 2 wherein separate insert-pieces are disposed within the channel of the cross-piece on either side of the body, and wherein the rollers are mounted on bolts running upward through the insert-pieces and the top wall of the cross-piece.

4. A construction according to claim 3 wherein the clamping means includes a bolt running from the channel-disposed portion of the guide-member upward through the slot in the top wall of the body, and an adjusting nut threadedly mounted upon the uppermost protruding end of

the bolt and constructed and arranged to be releasably tightened against the top wall.

5. A portable glass cutting device comprising an elongated body of inverted U-shaped cross-sectional configuration having a slot running longitudinally along its top wall, means for mounting a glass cutting tool at one end of said body, a guide-member mounted upon said body and movable longitudinally therealong, said guide-member including a cross-piece disposed transversely of said body and a portion of U-shaped cross-section disposed within the channel of the body, clamping means for releasably locking said guide-member to said body and including a bolt running from the channel-disposed portion of the guide-member upward through the slot in the top wall of the body and an adjusting nut threadedly mounted upon the uppermost protruding end of the bolt and constructed and arranged to be releasably tightened against said top wall, and a plurality of aligned rollers mounted on the underside of said cross-piece and disposed in right-angular relationship to the axis of the body, the rollers being positionable against an edge of a sheet of glass or the like whereby the cutting tool will extend downward and into contact with the upper face of the sheet; the cutting tool producing a score line parallel to, and spaced a predetermined distance inward from, said edge when the device is manually moved so that the rollers ride along the edge.
